① U.S. 1,928 Design for floor cloth
John Greenway, Inventor
Ethel Reward, Owner. Patented April 5, 1864.

UNITED STATES PATENT OFFICE.

GEORGE GREEN, OF WAPPINGER'S FALLS, ASSIGNOR TO DEBORAH POWERS,
ALBERT E. POWERS, AND NATHL. B. POWERS, OF LANSINGBURG, NEW
YORK.

DESIGN FOR A FLOOR-CLOTH PATTERN.

Specification forming part of Design No. 1,928, dated April 5, 1864.

To all whom it may concern:

Be it known that I, GEORGE GREEN, of Wappinger's Falls, in the county of Dutchess, in the State of New York, have invented or produced a new and original Design for Floor Oil-Cloths or other Fabrics; and I do declare that the following is a full and exact description of the same, viz:

The prominent and leading feature of the design consists of two bars of dark color placed at right angles with each other and diagonally upon the goods. At each side of these bars, midway between their intersections, is a projecting spur extending into the grounds lying between the bars and of the same color of the bars. Between these spurs upon the bar a spot of darker color is placed.

The grounds between the bars are of different colors from each other and from the bars. Upon the centers of these grounds is placed an ornamental figure, and each ground is separated from the bar by appropriate shadings, the whole being shown upon the accompanying drawings, which are hereby declared to form a part of this specification.

What is claimed, and desired to be secured by Letters Patent of the United States, is—

The design as shown upon the aforesaid drawings and described in the foregoing specification.

GEORGE GREEN.

In presence of—

JOHN GREEN,
ELIAS BROWN.
